UNITED STATES PATENT OFFICE.

JOHN KLEWANECH, OF ROYALTON, ILLINOIS.

MINE FIRE-FIGHTING APPARATUS.

1,421,496.

Specification of Letters Patent. Patented July 4, 1922.

Application filed May 25, 1920. Serial No. 384,080.

To all whom it may concern:

Be it known that I, JOHN KLEWANECH, a citizen of the United States, residing at Royalton, in the county of Franklin, State 5 of Illinois, have invented a new and useful Mine Fire-Fighting Apparatus; and I do hereby declare the following to be a full, clear, and exact description of the invention, such as will enable others skilled in the art 10 to which it appertains to make and use the same.

The invention relates to mine fire fighting apparatus and has for its object to provide a device of this character, comprising preferably an electrically driven car, to which car is coupled a tank car, and to provide hose connections with the tank car whereby various leads of hose may be led to the various branches of the mine. Also to provide the front of the car with a nozzle directed forwardly and having a hose connection with the tank car, thereby providing means whereby as the motor driven car moves into the tunnel of the mine, the water will be 25 directed on the fire therein.

With the above and other objects in view the invention resides in the combination and arrangement of parts as hereinafter set forth, shown in the drawings, described and 30 claimed, it being understood that changes in the precise embodiment of the invention may be made within the scope of what is claimed, without departing from the spirit of the invention.

35 In the drawings:—

Figure 1 is a sectional view through a portion of the mine tunnel showing the fire fighting apparatus therein.

Figure 2 is a horizontal sectional view 40 through a tunnel and some of the wing tunnels showing the apparatus in position for use.

Referring to the drawings, the numeral 1 designates a mine tunnel and three various 45 wings which extend outwardly from the tunnel. Disposed in the tunnel 1 is a track 4 on which the fire fighting apparatus runs.

The fighting apparatus comprises a preferably electrically driven car 5 and a 50 traile tank car 6, which is coupled to the car 5 as at 7. The forward end of the car 5 is provided with a platform compartment 8 on which the operator 9 stands for operating and controlling the apparatus. The 55 forward end of the car 5 is provided with a forwardly extending nozzle 10, which noz-

zle has connected to it a rearwardly extending pipe 11, which extends to the tank 6 from which it gets its supply of water, there being a flexible connection 12 so that the 60 pipe will not be broken as the apparatus as a whole moves around curves. Power for operating the car 5 may be obtained from an overhead wire 13 with which a trolley wheel 14 contacts, however, it is to be understood 65 that the car 5 may be run on storage batteries or if so desired an internal combustion engine may be used. The forward end of the tank 6 has secured thereto in any suitable manner a container 15, in which container 70 various hose sections 16 may be disposed. The hose sections 16 after the apparatus has been run into the mine may be removed from the container 15 and connected to any of the outlets 17 carried by 75 the forward end of the tank 6. By providing the auxiliary hose sections 16 it will be seen that lines of hose may be used by fire fighters in the wings 3, at the same time that the nozzle 10 is directing a stream forwardly 80 in the main tunnel 1. As the fires in the wings 3 are extinguished the apparatus moves forwardly, extinguishing the fire in the main tunnel and the wings as they are reached are entered by firemen with the hose 85 16 so that the fires therein may be controlled and extinguished.

From the above it will be seen that the fire fighting apparatus for fighting fires in mines is provided which is simple in construction and one wherein, as the apparatus enters the tunnel, a stream of water will be projected forwardly into the tunnel so as to extinguish the fire therein, said water being forced from the tank preferably by pressure 90 in the tank. It will also be seen that means is provided whereby as the fire fighting apparatus advances, the fires in various wing tunnels may be extinguished and controlled by means of the hose line 16.

100 The invention having been set forth what is claimed as new and useful is:—

A fire fighting apparatus for mines and the like, said apparatus comprising a motor driven car and a traile tank adapted to be 105 run into a mine tunnel, a coupling connection between the motor driven car and the traile tank, a horizontally disposed nozzle extending forwardly from the motor driven car at its forward end at a point spaced from 110 its lower side, a pipe connection between the nozzle and the traile tank, said pipe connec-

tion extending through the motor driven car and entirely housed therein, a flexible connection in said pipe located substantially above the coupling between the motor driven car and the trailed tank and a plurality of hose connections carried by the forward end of the tank and forming means whereby hose lines may be connected for extinguishing fires in wing tunnels after 10 water from the forwardly extending nozzle

has extinguished fire in the main tunnel beyond the entrance to the wing tunnel.

In testimony whereof I have signed my name to this specification in the presence of two subscribing witnesses.

JOHN KLEWANECH.
